ANTISKID SHOE DEVICE

Lill K. Frolich, Louisville, Nebr.

Application March 31, 1941, Serial No. 385,985

2 Claims. (Cl. 36—7.7)

This invention relates to anti-skid devices and has for an object to provide a device of small bulk, of economical construction which may be readily applied to and removed from a shoe in a position of use or readily folded and placed in a small sack for carrying said sack and contents in the user's pocket or a lady's purse.

Another object of the invention is to provide a device for anti-skid purposes having an inherent degree of resiliency for preventing accumulations of snow, ice particles and debris thereon during use.

Other and further objects and advantages of the invention will be understood from the following detailed description.

In the drawing:

Figure 1 is a side elevation of the new device applied as in use to a shoe, the latter being represented by means of dotted lines.

Figure 2 is a top plan view of a modification of the new device.

Figure 3 is a front elevation of the device shown in Figure 1.

As heretofore practiced in the art numerous anti-skid devices comprised primarily of metal have been produced which were either permanently attached to shoes or attachable by means of several buckles and straps, said prior device being bulky or not readily foldable whereby it has been found that people are loath to carry the same during inclement weather and at times when side walks and streets are covered with snow and the present invention aims to obviate the undesirable features of the prior practice.

Referring now to the drawing for a more particular description 10 indicates generally the anti-skid portion of the present invention, said member being formed of flexible cloth 11 having attached thereto or embedded therein a plurality of transversely disposed spaced apart elastic bands 12.

The member 10 is open at each end thereof whereby the toe of a shoe, the latter being upon the foot of a user, may be inserted through said openings, the narrower forward opening 13 thereof, in use, being disposed a few inches from the toe 14 of the shoe 15. The oppositely disposed side wall portions 16 of the member 10 extend from the toe opening 13 divergently and flaringly with respect to each other toward the other opening 17 at the wider end of the member 10 and as thus described it will be noted that the new device may be disposed in the position shown in Figure 1 with respect to the shoe 15 whereby said device is snugly disposed over the sole 18 and the

instep portion 19 of said shoe in a manner whereby the member 10 is prevented from movement towards the heel 20 of the shoe.

At opposite sides of the member 10 opposite ends of a resilient strap 21 are secured and in use the closed end 22 of the strap extends over the upper portion of the heel 20 of said shoe whereby the member 10 is prevented from movement towards the toe 14 of the shoe 15.

10 The elastic bands 12 extend across the bottom portion 23 of the member 10, being secured to and embedded within said bottom portion and opposite ends of said bands are respectively secured to and embedded in the oppositely disposed side 15 wall portions of the member 10. The portions of said bands which are disposed across said bottom 23 are of a normal length which is less than the distance across said bottom for maintaining said bottom limp across the sole 18 of the shoe 20 during use by means of the urge of said plastic bands, the latter being adapted to yield when stretched during bending movements of said sole incident to walking movements of a user's foot, at which time said bottom portion expands against the urge of said elastic bands, whereby during said walking movements the bottom 23 of the new device is subjected to forces which alternately contract said bottom portion at times when the sole 18 is raised off from the ground 25 and caused to expand during bending movements of the sole 18 resultant from the change in contour of the ball of a user's foot during said walking. As thus described it will be noted that said bottom portion 23 is caused to have, during use, 30 sufficient changes in contour and area to free said bottom portion of snow and debris which would otherwise normally cling to said bottom. 35

As thus described it will be noted that a user upon encountering icy pavements or the like may readily position one of the new devices upon each foot and that at times when the bottom portion of said device is in contact with pavement, that since said bottom is rugose, as shown, the feet of said user are prevented from 40 slipping or skidding upon snow and ice covered pavement, the flexing and bending of the member 10 during walking movements preventing compacted snow from accumulating upon the bottom portion 23 of the new device whereby 45 said bottom becomes automatically freed of debris during walking steps taken.

The new device is marketed in several assorted sizes for conforming to several different shoe sizes.

55 Referring to Figure 2 the modification there

depicted is similar in all respects to the device shown in Figure 1 with the exception of an additional feature now to be described.

The upper portion of the member 10 is bifurcated for a major portion of the length thereof. Oppositely disposed strips of cloth 30 and 31 are attached to the opposite edges of said bifurcations, said strips carrying metallic interlockable "Zipper" fastenings of well known design whereby at times when the slideable talon 32 is moved towards the end 13' of said modification, said edges are freed from each other and at times when the talon is moved to the position shown in Figure 2, said edges are attached together in a well known manner.

At times when the new device is provided with said "Zipper" mechanism the talon may be moved towards the toe opening 13' for facilitating placing the new device about a shoe and in the position shown in Figure 1; whereupon the talon is moved towards the opening 17' of the modification for causing the latter to engage snugly about the ball of the foot, the sole and instep of a shoe.

The new device may be readily removed from a shoe, folded and placed in a moisture proof bag for transportation in a lady's purse or the vest pocket of a gentleman and readily available for emergency use.

From the foregoing description it is thought to be obvious that an anti-skid shoe device constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish it to be understood as limiting myself to the precise arrangement and formation of the several parts herein shown in

carrying out my invention in practice except as claimed.

I claim:

1. An anti-skid shoe device comprising a flexible cloth member having an open narrower end and an oppositely disposed wider open end; oppositely disposed side wall portions; said walls being disposed convergently with respect to each other from said wider end toward said narrower end, a bottom portion disposed between and secured to said side wall portions, whereby said member may be readily disposed snugly across the instep, sole of said shoe and the ball of a person's foot carrying said shoe, said member being provided with a plurality of elastic bands disposed across and secured to said bottom portion, opposite ends of said bands being respectively secured to said side wall portions, those portions of said bands disposed across said bottom being of a normal length less than the transverse distance of said bottom, and an elongated resilient strap having its ends respectively secured to opposite sides of said cloth member, the closed end of said strap being adapted to engage across the upper portion of the heel of said shoe for preventing movement of said member away from said heel, said bottom portion being rugose for preventing skidding movements of said foot during walking movements of the latter, said bottom portion being adapted to contract under urge of said elastic bands and to expand against the urge of said bands during said walking movements, whereby snow and the like debris becomes freed from said bottom portion during use.

2. A device as defined in claim 1 the cloth member of which is bifurcated at its upper portion longitudinally of its length, oppositely disposed edges of said bifurcations being provided with a "Zipper" mechanism for securing said edges together for facilitating application of the device upon a shoe in a position of use.

LILL K. FROLICH.
